12 Claims. (CL 18—8)

This invention relates to the production of artificial filaments and is particularly concerned with the spinning of artificial filaments by the dry or evaporative method.

In the spinning of artificial filaments by the dry or evaporative method the spinning solution, e. g. a solution of cellulose acetate or other organic derivative of cellulose in acetone, is extruded through a spinning jet containing a number of orifices, so that the solution emerging from the orifices in the form of a number of filaments, enters an evaporative atmosphere in which the filaments harden and set by the evaporation of the volatile solvent therein. Although in many cases the number of orifices in a single jet is limited by the size of thread that it is desired to produce, there are various applications of dry-spun continuous filaments in which jets can advantageously be used having a number of holes far in excess of the number required for the production of threads to be directly used as such. For example, if the continuous filaments are intended to be cut into staple fibre, considerable economy would result if the number of holes per jet enabled extrusion to conform with the maximum drying capacity of the cell containing the jet. Again, a thread intended to be stretched to produce filaments of great strength (or, when cut, strong staple fibre) may have a very large number of filaments. There are, however, certain difficulties arising in starting the operation, and in bringing about initially the clean flow of the spinning solution through each of the orifices of a spinning jet containing a large number of orifices. Until every orifice is spinning the operation cannot be regarded as started, and the time spent in this operation depends on the number of orifices in the jet. Consequently the number of orifices is limited by the time that can economically be allowed for starting the spinning with the jet as a whole.

It is an object of the present invention to provide a method and means for facilitating the starting of spinning from a jet particularly with view to increasing the number of spinning orifices with which the jet may economically be provided.

According to the present invention, in the production of artificial filaments by the dry or evaporative method the spinning jet employed is, before being secured to a source of supply of spinning solution, first filled with a liquid compatible with the spinning solution, and then applied as quickly as possible to the source of

supply. In this way it may be ensured that each of the orifices in the jet is flowing freely and that there is freedom from air bubbles liable to clog the jet in the space immediately behind the jet. Although a solvent for the base material of the spinning solution, e. g. the same solvent as the one actually used in the solution, may be used, the liquid with which the jet is filled is advantageously the spinning solution itself, which, in order to restrict to a minimum evaporation of solvent in the interval of applying the filled jet to the source of supply, should be cold. The attention needed from the time the jet is applied to the pressure supply to the time when stable spinning is reached is much reduced, possibly because the exclusion of air from the inside of the jet proper prevents gel formation likely to produce blocking of the orifices. A plasticizer may likewise be used.

For the purpose of carrying out the invention the spinning jet together with filter sheets and associated parts forming with the jet a unit to be attached to the source of supply of spinning solution may first be attached to a header supplying for example, cold spinning solution under pressure, at a temperature of about 25° C. The liquid is supplied at a speed substantially lower than the speed at which spinning solution is supplied during spinning, and is allowed to run for about 10 to 15 minutes, the liquid emerging during the latter part of this time from the spinning orifices and clearing the jet of any air bubbles that may have been trapped therein. The jet assembly is then removed and attached as quickly as possible to the source of supply of spinning solution from which spinning is to take place. After attachment the jet is wiped and the spinning is started in the usual way. If cold spinning solution is the liquid supplied, the jet may point upwards from the header to facilitate the complete forcing out of the air. When the jet is removed from the header, the viscous nature of the solution prevents the solution from running out of the jet, and the jet filled with solution may be inverted and applied to the usual pendant supply pipe of the dry-spinning apparatus.

The above expedients refer to actions that may be taken before the jet is applied to the source of supply of spinning solution or to modifications in the form of the jet itself or its associated parts. In addition steps may be taken during the actual starting up operation itself to facilitate the clearing of any jet orifices that may be blocked. Thus the jet may be subjected

to a rapid hammering or vibration, e. g. with a pneumatic hammering tool operating on a wooden peg that is applied to the surface of the jet so that the vibrating pressure disturbs the spinning solution in the jet orifices and, by releasing tight orifices, promotes free flow through the orifices.

The carrying out of the invention will not be described in greater detail with reference to the accompanying drawing, in which

Fig. 1 is a diagrammatic section of the upper end of a dry-spinning cell with the jet in position;

Fig. 2 is a section of a jet fitting assembled on the supply pipe;

Fig. 3 is an elevation corresponding to Fig. 3 but showing the jet fitting dis-assembled;

Fig. 4 shows apparatus for filling a jet with cold spinning solution; and

Fig. 5 is a part-section of the pneumatic tool shown in use in Fig. 1.

Referring to Fig. 1, 1 is a spinning cell through which air is drawn upwardly by suction applied to an outlet pipe 2. The spinning solution is fed by a pump (not shown) to a candle filter 3 depending from the top of the cell, a jet fitting 4 being screwed to the bottom of the filter. A door 5 in the side of the cell provides access to the filter and jet.

The construction of the jet fitting 4 is shown in Fig. 2. The jet proper comprises a flanged metal disc 6 having a circular or other arrangement of orifices 7. The jet is clamped to a member 8, a layer 9 of filter material and a perforated plate 10 spaced from the layer 9 being interposed between the jet flange and the member 8. The member 8 is screwed to a short pipe 11 the upper end of which is provided with a conical seat 12 towards which a ball 13 is urged by a spring 14. A nut 15 provides for the attachment of the pipe 11 to a member 16 screwed on the supply pipe 17 leading from the bottom of the filter 3. The member 16 is provided with a conical seat 18 towards which a ball 19 is urged by gravity and by the pressure of the spinning solution passing through the pipe 17 and through an eccentric passage 20 in a block 21 which serves to retain the ball 19 within the member 16.

The jet fitting 4 is removed from the member 16 by slackening the nut 15. When the jet fitting is thus removed, the spring 14 presses the ball 13 against the seat 12 to shut off the interior of the pipe 11 from the atmosphere. At the same time, the ball 19 is forced downwardly against the seat 18 to prevent the entry of air into the member 16. Upon reassembly of the jet fitting on the member 16 a washer 21, interposed between the member 16 and the pipe 11, presses the balls 13, 19 away from their respective seats and an eccentric hole 22 in the washer permits the flow of spinning solution to the jet.

When a new jet is to be fitted to the candle 3, a jet fitting 4 with jet 6, filter 9, and perforated plate 10 duly assembled, is screwed on to an upwardly directed branch pipe 23 to which cold spinning solution under pressure is supplied by a pump 24 from a header 25. Spinning solution is forced through the jet for about 10-15 minutes at a slow rate. This causes the interior of the jet and jet fitting to be free of air and enables a free passage for spinning solution to be forced through all the orifices 7 of the jet. With the jet fitting thus entirely filled with cold spinning solution the fitting is re-

moved from the pipe 23, the ball valve 13 serving to prevent escape of spinning solution as the fitting is transferred to the spinning cell and screwed in place on the member 16. The jet fitting and the solution contained in it being cold, little evaporation of solvent takes place during the transfer of the jet fitting to the member 16. As soon as the jet fitting is in place, spinning solution, which is heated by its passage through the filter 3, is forced into the jet fitting and causes the cold spinning solution to be expressed, the cold spinning solution ensuring that by the time the hot solution reaches the orifices the passage through the orifices is maintained clear.

The perforated plate 10 has orifices less in size but greater in number than the orifices 7 in the jet 6 and thus serves to hold back or break up formations of small gels in the spinning solution which might lodge in the jet orifices proper and bring about stoppage of flow. The flow capacity of the disc 10 is greater than that of the jet cell and it therefore becomes immaterial if some of the small holes in the disc 10 become completely stopped.

When the initial mass of spinning solution that has collected on the lower face of the jet 6 has been wiped away, it may be found that one or more of the orifices 7 are still extruding with difficulty. To deal with this, use is made of the small hand pneumatic tool 26 conveniently connected by flexible hose 27 to an air line 28. The head of the tool is fitted with a wooden peg 29 which is applied to the face of the jet to subject the latter to rapid vibration, especially in the neighbourhood of the blocked orifices. This disturbs the spinning solution in the blocked or partially blocked orifices and rapidly frees them of their obstruction.

As already mentioned, plasticisers may be used. For spinning solution of cellulose acetate or other cellulose derivative, tricresyl phosphate, and dimethyl phthalate and other liquid alkyl phosphates are suitable plasticisers for filling the jet before spinning.

Having described our invention, what we desire to secure by Letters Patent is:

1. In the starting of a spinning operation for artificial filaments by the dry or evaporative method, filling the spinning jet with a liquid compatible with the spinning solution, and then applying the jet filled with the liquid to the source of supply of spinning solution.

2. In the starting of a spinning operation for artificial filaments by the dry or evaporative method, filling the spinning jet with a solvent for the base material of the spinning solution, and then applying the jet filled with the liquid to the source of supply of spinning solution.

3. In the starting of a spinning operation for artificial filaments by the dry or evaporative method, filling the spinning jet with spinning solution at a temperature below that of the solution to be spun, and then applying the jet filled with the solution to the source of supply of spinning solution.

4. In the starting of a spinning operation for artificial filaments of an organic derivative of cellulose by the dry or evaporative method, filling the spinning jet with a liquid compatible with the solution of said organic derivative of cellulose to be spun, and then applying the jet filled with the liquid to the source of supply of spinning solution.

5. In the starting of a spinning operation for

artificial filaments of cellulose acetate by the dry or evaporative method, filling the spinning jet with a solvent for cellulose acetate, and then applying the jet filled with the solvent to the source of supply of spinning solution.

6. In the starting of a spinning operation for artificial filaments of cellulose acetate by the dry or evaporative method, filling the spinning jet with a solution of cellulose acetate at a temperature below that of the solution to be spun and then applying the jet filled with solution to the source of supply of spinning solution.

7. In the starting of a spinning operation for artificial filaments by the dry or evaporative method, filling the spinning jet with a liquid compatible with the spinning solution, then applying the jet filled with the liquid to the source of supply of spinning solution and then applying vibrating pressure to the surface of the spinning jet in order to promote free flow through the jet orifices.

8. In the starting of a spinning operation for artificial filaments by the dry or evaporative method, filling the spinning jet with a liquid compatible with the spinning solution, then applying the jet filled with the liquid to the source of supply of spinning solution and then applying vibrating pressure by means of a pneumatic hammering tool to the surface of the spinning jet in order to promote free flow through the jet orifices.

9. In the starting of a spinning operation for artificial filaments by the dry or evaporative method, filling the spinning jet with a solvent for the base material of the spinning solution, then applying the jet filled with the solvent to the source of supply of spinning solution and then applying vibrating pressure by means of a pneu-

matic hammering tool to the surface of the spinning jet in order to promote free flow through the jet orifices.

10. In the starting of a spinning operation for artificial filaments by the dry or evaporative method, filling the spinning jet with spinning solution at a temperature below that of the solution to be spun, then applying the jet filled with the solution to the source of supply of spinning solution and then applying vibrating pressure by means of a pneumatic hammering tool to the surface of the spinning jet in order to promote free flow through the jet orifices.

11. A spinning jet connection for facilitating the attachment of a spinning jet filled with liquid to a source of supply of spinning solution, said connection comprising a valve on the end of the source of supply of spinning solution, an attachment to carry the spinning jet, and a valve on said attachment, said valves being adapted to close when the spinning jet is removed from the source of supply and to open when the spinning jet is attached to the source of supply.

12. Spinning jet connection for facilitating the attachment of a spinning jet filled with liquid to a source of supply of spinning solution, said connection comprising a ball valve on the end of the source of supply of spinning solution, an attachment adapted to carry a spinning jet, a spring-loaded ball valve on said attachment and a disc adapted to be secured between said attachment and the source of supply and to engage said ball valves so as to open them, said disc being eccentrically perforated to allow the passage of spinning solution through said valves and said disc.
